UNITED STATES PATENT OFFICE.

LUTHER T. HAWS, OF BERKELEY, CALIFORNIA.

SANITARY DRINKING-FOUNTAIN.

1,171,517.

Specification of Letters Patent.

Patented Feb. 15, 1916.

Application filed August 24, 1915. Serial No. 47,118.

To all whom it may concern:

Be it known that I, LUTHER T. HAWS, a citizen of the United States, residing at Berkeley, in the county of Alameda and State of California, have invented certain new and useful Improvements in Sanitary Drinking-Fountains, of which the following is a specification.

My invention relates to that class of drinking-fountains in which the construction and operation necessitate a hygienic use. In such fountains there are certain recognized features, such, for example, as contact preventive means, so that the user touches nothing but the flowing stream; and also there are constructive shapes and measures for keeping all surfaces of possible undesirable contact, clean, well washed and thoroughly drained. A common type of these sanitary fountains comprises a cock controlled water-supply pipe, a water delivery pipe fitted with some form or character of mouth guard, and a water-receiving drain-cup or bowl inclosing or enveloping the delivery pipe. Heretofore both the mouth guard and the drain cup have been made of relatively hard material, such as metal or porcelain. This construction, while well suited for most situations, is not adapted for others, as, for example, for moving vehicles, such as cars, trains and boats, where, due to the motion, the user is unsteady; or for hospitals and the like where the instability of the user is due to his own infirmity; or for any location in which, for any reason, there may be a want of steadiness in the user. In any of these cases injury may result by contact with hard surfaces of the drain cup or mouth-guard.

It is the object of my invention to provide against such injury, and thereby adapt my drinking fountain for the situations suggested. This object I attain, in essence, by making the drain-cup of relatively soft or yielding material, preferably soft rubber; and by making also, if desired, the mouth-guard of similar relatively soft material; and as the employment of these materials requires a novel construction, arrangement and combination of parts, my invention consists in the novel sanitary drinking-fountain which I shall now fully describe by reference to the accompanying drawings, in which—

Figure 1 is an elevation, partly in section, of my fountain. Fig. 2 is an elevation of

the same, partly broken, taken at right angles to Fig. 1.

1 is the water supply pipe, in which is included the shell 2 of the controlling valve or cock, which is here shown as operated by a push-button 3.

4 is the drain cup. This is made of soft, yielding material; in practice, of soft rubber. The base of the cup is extensively and rigidly clamped between an outer plate 5 and an inner plate 6, and said plates are themselves clamped between the upper end of a stem portion 7 of the valve shell 2 and a flange or collar 8 on the delivery-pipe 9. The lower end of the delivery pipe passes down through both clamp plates 5 and 6, and through the intervening base-center of the cup 4, and said end is exteriorly threaded, as shown, to receive and engage the interiorly threaded stem 7 of the valve shell 2. When, therefore, the two threaded portions are screwed home all the parts are firmly held together in operative relation, the rubber cup 4 being extensively clamped and so held as to be proof against dislodgment by tearing out, as would be liable to occur if it were held by a relatively small annular surface or edge, and were subjected to the sudden strain of a lurching user grabbing hold of it to steady himself.

10 is the mouth guard fitted upon the delivery pipe 9. This guard has the exit opening 11 for the issuing stream. The guard may be of any shape, straight or enlarged, but preferably spheroidal or of other curved surface, and large enough to discourage the user from taking it into his mouth. In practice I prefer to make this mouth-guard also of soft yielding material, say, of rubber. The cup 4 is fitted with a drain section 12 which is threaded to receive any fitting according to the direction which it is most convenient for the waste to take. It will now be seen that with these relatively soft surfaces, injury from contact will not follow, and the device is, thus, well suited for places, especially railway cars, where such contact is likely to take place. At the same time a simple, durable and efficient fountain is provided, which is clean and can be easily kept so.

I claim:—

1. A sanitary drinking fountain comprising a cock-controlled supply pipe having a threaded stem; a delivery pipe having a threaded lower end adapted to engage the

- threaded stem of the supply pipe, and having a collar above said lower end; a drain-cup of yielding material enveloping the delivery pipe; an outer clamp plate under the 5 base of said drain cup and bearing on the upper end of the supply pipe stem; and an inner clamp plate on the upper surface of the base of the drain-cup and bearing under the collar of the delivery pipe.
- 10 2. A sanitary drinking fountain comprising a cock-controlled supply pipe having a threaded stem; a delivery pipe having a threaded lower end adapted to engage the threaded stem of the supply pipe, and having a collar above said lower end; a mouth-guard of yielding material carried by the 15

delivery-pipe; a drain-cup of yielding material enveloping the mouth-guard; an outer clamp plate under the base of said drain cup and bearing on the upper end of the supply pipe stem; and an inner clamp plate on the upper surface of the base of the drain-cup and bearing under the collar of the delivery pipe.

In testimony whereof I have signed my 25 name to this specification in the presence of two subscribing witnesses.

LUTHER T. HAWS.
